UNITED STATES PATENT OFFICE.

THOMAS W. GREEN, OF PHILADELPHIA, PENNSYLVANIA.

ROTARY BLOWER.

1,004,776.

Specification of Letters Patent.

Patented Oct. 3, 1911.

Application filed March 24, 1911. Serial No. 616,728.

To all whom it may concern:

Be it known that I, THOMAS W. GREEN, a citizen of the United States, and a resident of Philadelphia, Pennsylvania, have invented a certain new and useful Rotary Blower, of which the following is a specification.

My invention relates to blowers and particularly to that type or character of blower in which two impellers alternate in position and coöperate to perform the locking or valve functions for each other.

One of the purposes of my invention is to provide plane faces for the lock or seal portions upon each impeller which coöperate with a blade of the other, in order to simplify the machining of these locks and to provide for adjustment to maintain effective seals with the blades notwithstanding wear, or variation in the relative angular positions of the two impellers because of wear to the connecting gearing or other parts.

A further purpose of my invention is to provide adjustment of the plane locking portions, preferably into parallel plane positions.

A further purpose of my invention is to provide reliable quick adjusting means for the plane surfaces involved and to make them capable of nice adjustment.

A further purpose of my invention is to provide for adjustment of the sealing lock angularly with respect to its length, which I prefer to accomplish by making the ends of the lock separately adjustable.

A further purpose of my invention is to equip the ends of impeller blades with sealing members which are made effective in proportion to the pressure used and by reason of it.

Further purposes of my invention and novel details of construction will appear in the specification and claims hereof.

In the drawings I have selected for illustration an embodiment of my invention which is highly practical, efficient and inexpensive, from among the many available forms.

Figures 1 and 2 are transverse vertical sections of the preferred form of my invention, corresponding to the section at $x-x$ in Fig. 3, but with the impellers in slightly different positions. Fig. 3 is a horizontal section of my invention corresponding to the section at $w-w$ in Fig. 1. Fig. 4 is a relatively enlarged elevation of a part of the structure

seen in Figs. 1 and 2, omitting the locking plate. Fig. 5 is a section corresponding to line $z-z$ of Fig. 4, but with the plate in place. Fig. 6 is a broken end elevation of the structure seen in Fig. 5. Fig. 7 is a relatively enlarged section of the outer end of one of the impellers of Figs. 1 and 2. Fig. 8 is a broken elevation, showing a modification of one part of my invention. Fig. 9 is a broken section upon line $y-y$ of Fig. 8.

The same reference numerals indicate like parts in the drawings.

In the form illustrated, 1 designates a casing or frame, here called a cylinder, semi-cylindrical in cross section at the parts 2 and 3 and straight between these parts. Within this two coöoperating impellers are placed. The casing is provided with two openings for the gas or liquid which is being pumped, one being the inlet and the other the outlet. Their character is determined by the direction of rotation of the impellers. With the direction indicated by the arrows in the figures, these become inlet opening 4 and outlet opening 5. The casing about these openings is provided with flanges 6 by which suitable piping is attached and the cylinder is flanged at its ends at 7 for attachment of cylinder heads 8 which carry the bearings 9 for the shafts 10, 11 upon which the two impellers are mounted. I provide suitable glands 12 for these bearings whenever gas is being pumped and the pressure is sufficient to make leakage there-through objectionable, and drive one of the impellers by the shaft of the other, in proper time relation thereto, through two equal gears 13 which are held in place by set screws 14 passing through bosses 15 upon the gears. Upon one end of one of the shafts, preferably that end opposite the gearing, I mount any suitable pulley or other driving device 16; so that the blades of one impeller 17 may be properly driven and timed to pass within the waist 18 of the other impeller 19, and vice versa.

For the purpose of assisting in the sealing function between the impellers and coöperating parts when handling gases and light liquids, and of making the tightness of the seal correspond in large measure with the need therefor by reason of the pressure used, I may groove the impellers longitudinally at their outer extremities as at 20, and insert therein sealing material of any suitable

character and corresponding shape as at 21, providing inlet openings 22 upon the leading side of the impeller, in the direction of rotation, by which the air which is being pumped may be admitted to the groove upon the inner side of the sealing material and may become effective to force the sealing material outwardly to perform its function. I prefer to make the groove of approximately 5 circular cross-section and to use sealing material of approximately the same section and smaller dimension. I have found leather quite satisfactory for the purpose. The cylindrical shape of the sealing material is 10 quite desirable as it results in slight rotation thereof in use, whereas regular polygonal shapes would require withdrawal and reinsertion with the other sides successively exposed to approximate the same distribution 15 of wear about the surface of the sealing material automatically attained by the circular form. The outward pressure upon the sealing material is made proportionate to the force tending to cause the air or other material to pass it.

The main aims of my invention, in so far as it relates to the sealing parts or faces of the waist of each impeller, are to secure ease and accuracy in the machining of these 20 parts and to make them adjustable. I attain the first aim by making these parts plane upon their surfaces and further simplify the construction, as well as the laying out of this work in the shop, by making the 25 plane face upon one side of the impeller which forms part of the surface of one waist lie within the same plane as that face upon the other side of the impeller which forms a part of the opposite side of the other waist. 30 I also make the other two plane waist surfaces coöoperating respectively with the two above stated, as parts of another plane at right angles to the plane first stated.

The adjustability attains three advantages. It permits the two plane surfaces upon opposite sides of the same waist to be 35 adjusted, one outwardly and the other inwardly, to compensate for lag or lead of one impeller angularly with respect to the other because of wear of the connecting 40 gearing, permits adjustment of any one or all of the plane faces to provide for wear of the faces themselves or of the impellers, and, with independent means for adjusting the 45 different ends of the planes, makes it possible to accommodate the plane faces to the impellers during construction or erection when their faces are not strictly parallel, whether because of strain or whatever 50 other reason. To secure these benefits, I form portions 23 of the locks or cut-offs of my impellers as plane surfaces with which the outer, preferably belled, portions 55 60 of the blades coöperate. I have found 65 the most desirable arrangement of these to

be that in which these planes are radial to the impeller axes and adjoining planes are at right angles to each other, with the result that the faces of 23 and 23' lie within the same plane, while the faces of 23² and 23³ also both lie within another plane which is at right angles to that containing 23 and 23'. I prefer to place the outer limiting edges of these plane surfaces within the pitch circles 25 and to determine the inner limiting edges of these plane surfaces with relation to the sealing line of the portions 24 therewith at the time that the impeller begins to seal with another of the plane faces. I extend the plane surfaces toward the center of the impeller sufficiently to have a reasonable lap of these seals, both to insure effective sealing of the one before the seal is released by the other and also to provide for variation of the exact lines at which both seals become effective after wear of the gearing and angular variation of the relative positions of the impellers take place. While I am providing primarily in my adjustment for the wear in the gearing with 70 corresponding relative angular variation in position of the two impellers, and for canting of the seals to bring them into parallelism with the coöperating impeller surface, it is evident that wear of any character which 75 might occur between the rotating parts can also be provided for by the same adjustment.

While the exact curvature of the impeller blade could be determined experimentally, I prefer to determine the various centers of curvature as follows: From the center of that part of the pitch circle 25 lying within each blade as at 26, between the points 27 at which the pitch circle cuts the planes 23, 23', 23² and 23³, I set off points 28 upon a tangent 29 drawn to the pitch circle through the point 26. These points 27 and 28 are, therefore, at a distance from 26 corresponding to the chord of one-eighth of the pitch circle. I then connect opposite points 27, 28 as indicated. From the points 26 I next draw lines 26-30 which are chords of quarters of the pitch circle. The intersections of these lines 26-30 with the lines 27-28 at 31 and 32 give the centers about which I 100 describe the portions 33 of the blade, using each of these centers to describe the curve upon that face of the blade farthest from said center. The connecting curves between portions 33 and the plane surfaces are drawn 105 from centers 25' upon the pitch circle midway between 26 and 27. Each center 25' is used for the curve upon the side of the impeller nearer to it. The character of the 110 curve forming the end of the impeller between the points 34 at which the curves 33 so determined leave the plane coöperating surfaces of the seals 23, 23', etc., giving 115 allowance for sufficient lap, may vary considerably and is laid out to coöperate with 120 125 130

the curvature of the parts of the waist of each impeller between the plane faces, so as to trap as little air as possible therein and to give proper waist width for the impeller shaft and reasonable impeller strength thereabout.

I have found that the method of designing the curves of my impeller blades, as above defined, forms effective blade surfaces for coöperation with the plane sealing faces placed upon quadrants as described and it may be used alternatively to experimental charting by movable models. Obviously, if other positions than quadrants are selected for the plane faces, corresponding differences in the impeller blade curves will be required and these can be determined practically with ease.

The plane surfaces of the locks or cut-offs may be easily and accurately laid out and machined and are very desirable even when not adjustable. They may be made adjustable in any of a great variety of ways of which I have shown but two, one illustrating nicety and ease of adjustment and the other simplicity of construction.

In the form shown in Figs. 5 and 6, I groove the impeller longitudinally at 36 throughout its length, and with its depth preferably tangential to the pitch circle, to provide seats for plates 37, and cut it deeper at each edge to provide spaces 38 within which the operating lugs of wedges 39 are placed. The plates 37 form the effective sealing faces, coöperating with the blades or vanes of the impellers and are adjusted by means of the wedges 39, which may be moved independently, but which are moved toward or away from each other to effect or permit outward or inward movement of the plates 37 through parallel positions. If the wear toward different ends of the machine be different, or the machine be set up in a position to cause uneven stress or twist upon the surfaces, the variation can be taken up by adjusting one only of the wedges.

The movement of the plates 37 outwardly is here shown as limited by two sets of means, shown as screws, of which the set 40 at all times takes the outward strain brought upon the plate by the wedges 39 as these are drawn toward each other by the screws 41. Before effecting additional outward movement of the plate 37, therefore, one or both of the screws 40 must be slackened to the desired extent, after which the wedge or wedges 39 are forced in to take up the slack by means of screws 41. Within the impeller body at this point are cast or otherwise located sockets 42 whose openings, best seen in Fig. 4, are of keyhole form, being enlarged at 43 to permit the passage of heads 44 of screws 45, while the openings are smaller at 46 to retain heads 44 therein. The plates are inserted with the screws 45 in place by passing the heads 44 through the

openings 43. The plates are then moved longitudinally to position with the parts as shown in Fig. 5, after which the wedges 39 are put in place and the screws 40 and 41 are inserted.

The screws 45 are intended to limit the ultimate outward movement of the plates 37, particularly in case of withdrawal, accidentally or otherwise, of the screws 40. Both sets of screws 40 and 45 are intended to protect against outward strains but both are protected against strains due to centrifugal forces by the engagement of plates 37 with the edges 47 of the openings 36 in the impellers. Since the plates lie, preferably, with their faces in radial position with respect to the impeller shaft, the centrifugal strains will be received squarely upon the preferably tangential edges 47 of the impeller and there will be no shearing nor other centrifugal strains upon any of the screws or fastenings used. The wedges 39 are recessed at 39' to allow adjustment without interference with the screws 40.

In the form shown in Figs. 8 and 9 the same grooves 36 are used to provide seating for the adjustable faces, and the same edges 47 receive the radial thrust due to any centrifugal action present. The plate 37' is retained finally by the dovetailed part 48 fitting in the corresponding groove 49 and permitting insertion of this member from the end. Here liners of different thickness or successively changed number are intended to be inserted at 50 and the plate is drawn back rigidly against them by means of screws 51 passing through the material of the impeller.

It will be evident that other forms of adjustment than by wedges or liners, and other securing and operating means than by screws, may be used and that a similar action might be obtained by movement of the plane surfaces in other directions than that indicated to effect the adjustment. Whatever form of adjustment is used, all of the faces are, preferably, initially set at an intermediate position in their range of adjustment. When wear of the gearing requires adjustment, one of the two faces upon the same side of the impeller is set farther out and the other farther back in the impeller to bring the faces into operative relation to the blade of the other impeller, whether it be lagging or leading. Wear upon the lock faces may also be compensated by outward adjustment of the face which is worn. Some of the advantages of the plane face may be attained by close approximations thereto even when not adjustable, and my invention contemplates adjustability of the locking faces which are not plane nor approximations thereto. In the form illustrated, the waist of each of the impellers is made use of as a valve, sealing against leakage during the passage of the blade of the other im-

peller, with interchange of these sealing functions successively by the waist and blade of the two impellers alternately and so as to maintain a continuous seal between the impellers at all times. In each sealing co-operation of one side of the waist of one impeller with the blade of the other, the blade coöperates with two sealing waist faces, each of which faces in coöperation with a blade 10 presents an embodiment of one part of my invention. The plane faces, whether adjustable or not, perform valve functions only in these relations, and are capable of uses where the rotor upon which they are mounted is a valve only, and never an impeller. I have, therefore, considered the one member as an impeller and the other as a valve only, in some of the claims.

Having thus described my invention what I claim as new and desire to secure by Letters Patent is:—

1. In a blower, a pair of impellers, each having blade and lock portions, the blade of one coöperating with the lock of the other, and plane lock portions upon each impeller.
2. In a blower, a pair of impellers having belled blade portions and plane facings for lock portions, the blade portions of each impeller coöperating with the lock portions of the other.
3. In a blower, a pair of impellers having their blades belled and their lock portions lying substantially in planes radial.
- 35 4. In a blower, an impeller having belled blades in combination with a rotary member locking with the blades and having its locking surfaces plane.
5. In a blower, an impeller having belled 40 blades in combination with a rotary locking member, a movable facing coöperating therewith and means for substantially tangentially adjusting the facing.
6. In a blower, an impeller having blades 45 in combination with a rotary locking member therefor, providing separate lock faces for each blade and a substantially tangentially adjustable facing upon said locking member.
- 50 7. In a blower, an impeller having blades in combination with a rotary locking member therefor, plane faces for the locking portions and means for adjusting these facings.
8. In a blower, an impeller having belled 55 blades in combination with a rotary lock, plane locking faces therefor and means for

adjusting the locking faces tangentially with respect to the rotary locking member.

9. In a blower, an impeller having belled blades in combination with a rotary locking 60 element having its locking faces lying substantially within quadrant planes through the axis of its rotation.

10. In a blower, an impeller blade, a rotary sealing member therefor, an adjustable 65 locking plate for the member and separate adjustments for different ends of the lock.

11. In a blower, a pair of belled impellers, each impeller having belled blades on opposite ends and a lock on each side between the blades for one of the blades of the other impeller and having plane faces upon opposite sides of each lock.

12. In a blower, two coöperating impellers, each having two belled blades and 75 intermediate plane sided locks.

13. In a blower, a belled blade having one side plane and approximately radial in proximity to the waist for engagement with another impeller.

80 14. In a blower, an impeller blade, a rotary sealing member therefor, a movable sealing face for the sealing member, longitudinally movable wedges for moving said face, means for moving the wedges and 85 means for limiting the movement of the sealing face.

15. In a blower, an impeller, a rotary sealing member therefor, a movable seal upon said member, wedges for moving said 90 seal, means for limiting the movement of the seal and additional means for limiting the ultimate movement of the seal.

16. In a blower, an impeller, a rotary member coöperating therewith and, longitudinally grooved to provide a substantially tangential abutment, a removable locking face for the impeller located in said groove and resting against the abutment and means for adjusting the position of said face in a 100 tangential direction.

17. In a blower, an impeller blade, a rotary locking member therefor longitudinally grooved to form a seat for a locking facing, a facing therefor, means admitting said facing by longitudinal movement and limiting the outward movement thereof and means for adjusting the facing.
